United States Patent Office

Des. 180,441

Patented June 11, 1957

180,441

MODEL TRAIN TRACK SUPPORT

William Dian and Harvey Kramer, New York, N. Y.

Application July 11, 1956, Serial No. 42,210

Term of patent 3½ years

(Cl. D34—15)

Fig. 1

Fig. 2

Fig. 3

Figure 1 is a plan view of a model train track support showing our new design.

Figure 2 is a fragmentary perspective view, slightly enlarged, as seen from above Figure 1, from the right.

Figure 3 is a fragmentary perspective view, slightly enlarged, as seen from above Figure 1, from the left.

We claim:

The ornamental design for a model train track support, as shown.
